(57) **CLAIM**

The ornamental design for a beverage maker as shown and described.

DESCRIPTION

FIG. 1 is a top, rear perspective view of a first embodiment of a beverage maker showing our new design;

FIG. 2 is a bottom, rear perspective view thereof;

FIG. 3 is a front view thereof;

FIG. 4 is a rear view thereof;

FIG. 5 is a side view thereof;

FIG. 6 is an opposite side view thereof;

FIG. 7 is a top view thereof;

FIG. 8 is a bottom view thereof;

FIG. 9 is a top, rear perspective view thereof, shown in a condition of use;

FIG. 10 is a top, rear perspective view of a second embodiment of a beverage maker showing our new design;

FIG. 11 is a bottom, rear perspective view thereof;

FIG. 12 is a front view thereof;

FIG. 13 is a rear view thereof;

FIG. 14 is a side view thereof;

FIG. 15 is an opposite side view thereof;

FIG. 16 is a top view thereof;

FIG. 17 is a bottom view thereof; and,

FIG. 18 is a top, rear perspective view thereof, shown in a condition of use.

The uneven-length broken lines immediately adjacent to the shaded areas define the bounds of the claimed design and form no part thereof. The even-length broken lines depicting the remainder of the beverage maker form no part of the claimed design. The beverage maker is shown with a symbolic break in length. The appearance of any portion of the beverage maker between the break lines indicated by brackets forms no part of the claimed design.
